UNITED STATES PATENT OFFICE.

OTIS J. TRUESDELL, OF FARLINGTON, KANSAS.

BALING-PRESS.

SPECIFICATION forming part of Letters Patent No. 393,086, dated November 20, 1888.

Application filed May 5, 1888. Serial No. 272,929. (No model.)

To all whom it may concern:

Be it known that I, OTIS J. TRUESDELL, a citizen of the United States, residing at Farlington, in the county of Crawford and State 5 of Kansas, have invented a new and useful Improvement in Baling-Presses, of which the following is a specification.

My invention is an improvement in baling-presses; and it consists in certain novel features hereinafter described and claimed.

In the accompanying drawings, Figure 1 is a side view of my improved press. Fig. 2 is a plan view, partly in horizontal section; and Fig. 3 is a detail perspective view of the 15 cam-plate, a portion of the pitman, and connections between the same and its connections.

Referring to the drawings by letter, A designates the frame-work of my improved press, 20 having the usual feed-opening, B, and the press-box C. In the outer end of the frame-work I mount the pivot-pin or king-bolt D, on which the sweep E and the cam-plate F are fulcrumed. The sweep and the cam-plate are mounted 25 loosely on the king-bolt or pivot-pin, and are not connected together. The cam-plate is provided on its upper surface with a series of lugs, G, which are acted upon by the sweep to actuate the cam-plate, and thereby operate the 30 plunger, as will be presently more fully described. The inner end or edge of the cam-plate is formed on the arc of a circle, and is provided with a groove, H, running its entire length. The cam-plate is further provided 35 on its side edges with the lateral shoulders J J, the function of which will presently appear.

K designates the pitman, connected at its inner end to the plunger, as will be readily understood.

L designates two links, which are pivoted to the side edges of the cam-plate near the shoulders J J, and have their outer free ends connected to the outer end of the pitman by 40 cables M, as shown.

N designates two steadyng-bars, which have their inner ends pivoted to the outer end of the pitman and their outer ends pivotally mounted on the king-bolt or pivot-pin.

From the foregoing description, taken in 50 connection with the accompanying drawings, the operation of my device will be readily understood. The hay is placed in the press-box in the usual manner and the sweep moved from side to side.

55

It will be observed that the sweep is not connected to the cam-plate, and that the lugs on said plate are arranged at a distance apart slightly greater than the width of the sweep. The sweep is thus allowed to acquire a slight 60 momentum before coming into contact with the lugs on the cam-plate, and the said plate is consequently set in motion very easily without any sudden jar, as the momentum of the sweep aids the force applied to the outer end 65 of the same in overcoming the inertia of the cam-plate and setting it in motion. The cam-plate, being thus set in motion, will swing around until one of its shoulders J comes into contact with the adjacent link L, when 70 it will carry the said link around with the plate, thereby drawing on the pitman through the cable. The steadyng-bars, besides causing the pitman to move smoothly and evenly, serve to prevent its being drawn from side 75 to side in a straight line and give it a circular movement, thereby causing the plunger to move in and out at each stroke of the sweep.

Having thus described my invention, what 80 I claim, and desire to secure by Letters Patent, is—

1. In a baling-press, the combination of the king-bolt with the sweep and the cam-plate independently mounted thereon, the pitman 85 connected to the cam-plate, and the steadyng-bars mounted on the king-bolt and pivoted to the pitman, as set forth.

2. In a baling-press, the combination of the king-bolt with the cam-plate and the sweep 90 independently mounted on the same, the said cam-plate having a series of lugs on its upper surface arranged in the path of the sweep, the pitman connected to the cam-plate, and the steadyng-bars mounted on the king-bolt 95 and pivoted to the pitman, as set forth.

3. The combination of the king-bolt, the sweep, and the cam-plate independently

mounted on said king-bolt, the said cam-plate having shoulders on its sides, with the links pivoted to the cam-plate adjacent to said shoulders, the pitman, the cables connecting the links to the pitman, and the steadyng-bars mounted on the king-bolt and pivoted to the pitman, as set forth.

In testimony that I claim the foregoing as my own I have hereto affixed my signature in presence of two witnesses.

OTIS J. TRUESDELL.
